UNITED STATES PATENT OFFICE.

FRANK RHIND, OF MERIDEN, CONNECTICUT, ASSIGNOR TO EDWARD MILLER & COMPANY, OF SAME PLACE.

LAMP.

SPECIFICATION forming part of Letters Patent No. 357,412, dated February 8, 1887.

Application filed September 27, 1886. Serial No. 214,620. (No model.)

To all whom it may concern:

Be it known that I, FRANK RHIND, of Meriden, in the county of New Haven and State of Connecticut, have invented a new Improvement 5 in Lamps; and I do hereby declare the following, when taken in connection with accompanying drawings and the letters of reference marked thereon, to be a full, clear, and exact description of the same, and which said 10 drawings constitute part of this specification, and represent, in—

Figure 1, a sectional side view of a student-lamp illustrating the invention. Figs. 2 and 3 are modifications.

15 This invention relates to an improvement in the class of lamps in which the fount is made separate from the wick-chamber, and in which a conductor leads the oil from the fount to the wick-chamber—such, for illustration, 20 as that commonly known as “student-lamps.”

The object of my invention is such a construction of glass-lamp fount as will prevent the possibility of leakage.

In the accompanying illustration I show a 25 student-lamp in which A is the base; B, the standard upon which the slide C is arranged, and through which the connecting-tube D extends in the usual manner, and carrying the wick-chamber E at one end, on one side of the 30 upright, and the fount on the opposite side.

I make the body of the fount F of glass, its 35 bottom open, preferably nearly the full diameter of the fount. The outline of the fount may be to suit the tastes of the manufacturer or the demands of the trade. Around the 40 lower edge of the fount is a flange, G, the periphery of which gradually contracts from the extreme lower edge up to a shoulder, I, as shown. The top J of the fount may be of 45 glass, integral with the side or body of the fount, and is best made with a central filling-opening, K.

The bottom L of the fount is made from 50 metal, with a central depression, M, which 45 forms a cavity in the bottom of the fount. Around the outer edge of the bottom and upon the upper side a groove is formed to receive 55 the flange G, the bottom being made from

sheet metal. The bend in the metal to make the groove may be so as to give an ornamental 50 shape to the exterior of the metal, as shown. The groove is of considerably larger extent than the flange G, and so as to leave a space upon both sides of the flange G. This groove is filled with a cement that is proof against the 55 action of kerosene, as in Patent No. 342,463, granted to me May 25, 1886, *a* representing the cement. The diameter of the flange contracting, as before described, makes it of a dovetail shape, so that as the cement hardens 60 the flange becomes interlocked through the cement with the bottom. The side of the groove in the bottom is made of an irregular 65 shape, so that the cement interlocks with the bottom, and after the cement is set separation of the fount and bottom is impossible.

The conductor D enters the depression M in the bottom, and a metallic connection is there made, thus readily permitting a metal joint, through which the oil cannot pass. Preferably 70 the fount is covered with a metal cap, N, which also serves to close the filling-opening K.

I have represented the depression M in the bottom as of cup shape and made integral 75 with the bottom; but the conductor D itself may form the depression in the bottom, into which the oil will pass from the fount, as seen in Fig. 2.

While I prefer to construct the flange inclined to the axis of the fount, as I have illustrated, it may be otherwise constructed to interlock with the cement—say as seen in Fig. 3—it only being essential that the flange shall 85 present an annular interlocking surface, with which the cement will engage.

From the foregoing it will be understood that I do not claim, broadly, a glass fount having a metal bottom attached thereto by a cement impervious to oil; but

What I do claim is—

A lamp-fount the body F of which is made from glass and with its bottom open, and constructed with a flange, G, around its lower edge, presenting an annular interlocking surface, combined with a metal bottom, L, hav-

ing a depression therein, from which the conductor D leads to the wick-chamber, and with a groove near its outer edge adapted to receive the said flange G of the body, the said 5 groove also constructed to present an interior interlocking surface, the said flange of the

fount embedded in cement impervious to oil in said groove, and whereby the bottom and fount are interlocked, substantially as described.

FRANK RHIND.
